[57] ABSTRACT

In a color television receiver using a three-gun color CRT with three sets of internal pole pieces, a separate external dynamic convergence assembly is located adjacent each set of internal pole pieces. Two of the three convergence assemblies incorporate magnetic flux rotation means for unbalancing the magnetic flux field across the associated internal pole pieces to deflect an electron beam along an axis skewed to a radial direction. The flux rotation is produced by various combinations of a single deflection coil located on only one leg of a U-shaped core, locating a single pole shoe between one leg of the core and the CRT, and connecting pairs of deflection coils in phase opposition.

DYNAMIC CONVERGENCE SYSTEM

BACKGROUND OF THE INVENTION

This invention relates to dynamic convergence apparatus for a cathode ray tube, and more particularly to convergence apparatus which produces unsymmetrical magnetic fields across internal convergence pole pieces.

Typical dynamic convergence assemblies cause each of three electron beams to be deflected along three radial axes which intersect at the center of a tri-color CRT. While radial beam movement is desirable for the blue electron beam, which is generally oriented to that radial movement coincide with a vertical plane, radial beam movement of the red and green electron beam produces both vertical and horizontal motion. The resulting convergence control is interactive and hence difficult to adjust. For the red and green beams, therefore, lateral rather than radial deflection is desirable.

Various convergence apparatuses have attempted to provide non-radial dynamic convergence. For example, in Hooghordel et al U.S. Pat. No. 3,441,788, lateral convergence is accomplished by using an unsymmetrical convergence system having four external pole pieces adjacent a CRT with three sets of internal pole pieces. While such structure provides lateral beam movement, the configuration of the internal pole pieces is not conventional, nor is the external structure readily adapted for use with a conventional CRT having internal pole pieces formed by pairs of symmetrical L-shaped members.

Depending on the particular CRT being used, convergence correction by deflections other than lateral or radial may be desired. Prior convergence assemblies could not be adaptable to provide a variety of beam deflections which are skewed from the radial direction. Also, it would be desirable to simplify prior convergence assemblies, and to reduce the amount of energy required to effect convergence.

SUMMARY OF THE INVENTION

In accordance with the present invention, a novel convergence assembly generates nonsymmetrical magnetic flux fields between a pair of symmetrical internal convergence pole pieces. The asymmetry of the magnetic flux field can be altered to suit particular applications, thereby providing radial convergence for one color beam and lateral convergence for the remaining color beams in a color television receiver. However, other combinations and configurations are possible, as desired.

Several embodiments are disclosed for generating a nonsymmetrical magnetic flux field across a pair of magnetic pole pieces. In accordance with one embodiment, a U-shaped core has a convergence coil wound on only one leg. The leg carrying the coil contains a magnetic shoe located between the end of the core leg and the glass envelope of the CRT. In other embodiments, additional coils connected in phase opposition, and/or sources of phase opposed convergence signals, provide unbalanced magnetic flux fields.

By changing the ratio of leakage flux to flux circulating through the core of the external convergence assemblies, the amount of skewed beam movement can be adjusted. The amount of energy required to effect convergence is lower, resulting in a more efficient system. Also, the number of components has been re-

duced, making the convergence system more economical and easier to construct.

One object of this invention is the provision of a dynamic convergence assembly for producing an unsymmetrical magnetic flux field between a pair of symmetrical pole pieces.

Another object of this invention is the provision of a dynamic convergence assembly having a U-shaped core, and a convergence coil wound on only one leg of the core in order to produce beam deflection skewed from a radial direction.

Other objects and advantages of the invention will be apparent from the following description, and from the drawings. While illustrative embodiments of the invention are shown in the drawings and will be described in detail herein, the invention is susceptible of embodiment in many different forms and it should be understood that the present disclosure is to be considered as an exemplification of the principles of the invention and is not intended to limit the invention to the embodiments illustrated.

BRIEF DESCRIPTION OF THE DRAWINGS

FIG. 1 is a cross-sectional view of a conventional color CRT with internal convergence pole pieces, and illustrating an external convergence system constructed in accordance with the present invention;

FIG. 2 is a vector diagram of various possible paths of movement of the green and red electron beams shown in FIG. 1;

FIG. 3 is a cross-sectional view similar to FIG. 1, showing a modified form of the external convergence system and the magnetic flux field generated thereby; and

FIG. 4A shows another embodiment of a single convergence assembly, while FIG. 4B illustrates the electrical schematic thereof.

GENERAL SYSTEM OPERATION

FIG. 1 illustrates in cross-section the neck of a conventional three-gun color cathode ray tube (CRT) 20 incorporated in a color television receiver of known construction. The CRT has three identical gun structures for generating three electron beams which impinge blue (B), green (G) and red (R) phosphors on the face of the CRT. For convenience, similar structures will be identified by the same reference numeral, followed by the designation B, G or R to indicate whether the same is associated with the blue, green or red electron beam guns, respectively.

Within a glass tube envelope 22, a magnetic shield 24 divides the neck of the CRT into three compartments associated with the B, G and R electron guns, which are symmetrical about a radial axis. In the absence of a convergence magnetic flux field, an electron beam 30 travels undeflected along an axis perpendicular to the plane of FIG. 1 and equidistant from the spaced pole pieces 26, 27. Each internal pole piece 26, 27 is of generally L-shaped cross-section, comprised of a radially extending section, and a transverse section in contact with the glass envelope 22. The illustrated internal pole structure is well known and is typical of many color picture tubes.

To effect dynamic convergence of the blue electron beam, a known type of convergence yoke assembly is provided. A U-shaped ferrite core is formed by a pair of adjacent legs 32 and 34, each of L-shape. An air gap

36 separates the adjacent core legs. A vertical convergence coil is formed by two identical coil sections 38 and 40, wound on the legs 32 and 34, respectively. The coil sections 38, 40 are series connected and may be coupled to any conventional vertical convergence circuit in the television receiver.

In response to convergence current flowing in coil sections 38 and 40, equal magnetic flux fields are generated in legs 32 and 34 and a symmetrical or balanced magnetic field is produced between the internal pole pieces 26B and 27B. The blue electron beam 30B is deflected in a direction perpendicular to the symmetrical magnetic flux field, illustrated by the dashed lines, which exists across the mirror symmetry pole pieces. This causes the blue electron beam 30B to move in a radial direction as illustrated by the vector arrows.

To adjust for static convergence, a permanent magnet 42 spans the air gap 36 and has poles abutting each leg 32, 34. The permanent magnet 42 may be rotated, or otherwise suitably moved with respect to the orientation of its magnetic North and South fields, in order to alter the direction and magnitude of the steady magnetic flux field which circulates through the U-shaped legs 32, 34.

In prior convergence systems, the structure for the green (G) and red (R) assemblies would be identical with the blue (B) structure. This would cause all three electron beams 30 to be deflected in radial directions. While radial deflection is desirable for the blue beam 30B, due to the fact that the blue gun structure is oriented in a vertical plane, radial deflection of the green 30G and red 30R electron beams produce vector components in both the vertical and horizontal planes. The vertical component of movement for the red and green beams is frequently unnecessary and is, therefore, undesirable.

In accordance with the present invention, the green dynamic convergence assembly and the red dynamic convergence assembly are modified so as to produce a nonsymmetrical or unbalanced magnetic flux field between the pole pieces 26, 27 associated therewith. This field skews the path of deflection of the associated electron beam, and produces essentially lateral green 30G and red 30R beam movement, as illustrated in FIG. 1. Each modified dynamic convergence assembly utilizes a single vertical convergence coil 50 wound on only one leg of the U-shaped core. The green convergence coil 50G is wound about core leg 34G, while the red convergence coil 50R is wound on the core leg 32R.

In addition, the core leg carrying the single vertical deflection coil 50 terminates in a face abutting a pole shoe 52 sandwiched between the core leg and the glass envelope 22. The opposite or free core leg has no pole shoe, thus creating an air gap 54 between the end face of the core leg and the glass envelope 22. The air gap is substantially the same width as the pole shoe 52. The net effect of the single vertical coil 50, the pole shoe 52, and the air gaps 36 and 54 is to change the magnetic flux pattern produced in the vicinity of the electron beam 30. The magnetic flux fields, as illustrated by the dashed lines adjacent the electron beams 30G and 30R, are no longer symmetrical or balanced between the pole pieces 26 and 27.

The flux shift results because the magnetic flux passing through the core legs 34G and 32R is considerably greater or more concentrated than the flux passing through the opposed core legs 32G and 34R. Although

leakage flux was present in prior convergence assemblies, the balanced or symmetrical construction of the assemblies, such as shown by the blue assembly, produces a balanced leakage flux distribution which results in a total flux distribution between the pole pieces which is balanced and produces radial beam movement.

In FIG. 2, the effect of the nonsymmetrical magnetic fields is illustrated for the green 30G and red 30R electron beams. The vectors 60 illustrate a radial path of beam deflection, which would be produced by a balanced coil design such as the blue convergence assembly. When only the green convergence coil 50G of FIG. 1 is energized, the green electron beam 30G has a path of movement as illustrated by vector 62G. Similarly, when only the red convergence coil 50R of FIG. 1 is energized, the red beam 30R has a path of movement as illustrated by vector 62R.

However, when both deflection coils 50G and 50R are energized at the same time, the paths of deflection of electron beams 30G and 30R are substantially parallel and lateral, as shown by vectors 64G and 64R. This improved efficiency when both coils 50G and 50R are energized demonstrates the importance of the leakage flux in determining the direction of beam movement. It should be noted that leakage flux is defined as flux which does not emanate from either of the faces or poles of the core legs 32, 34. The ratio between the leakage flux and the flux flowing through the core into the pole pieces, is important in determining the direction of the magnetic flux lines in the vicinity of the electron beam, and hence the direction of beam movement.

MODIFIED EMBODIMENTS

In FIG. 3, modified green and red convergence assemblies are illustrated in which the single convergence coils 50G and 50R are located on the upper core legs 32G and 34R, respectively. For clarity, the blue convergence structure is not illustrated. No pole shoe is located between the core leg carrying the coil 50 and the glass envelope 22, reducing the imbalance. The FIG. 3 embodiment is desirable when a particular cathode ray tube requires maximum vertical deflection to correct for convergence errors. A substantial flux component 70 extends between core legs 32G and 34R, via the magnetic shield 24 and across the internal pole pieces 26B and 27B. This flux component is also found in the embodiment of FIG. 1, but extends between core legs 34G and 32R, and is generally external and adjacent to the glass envelope 22. In both cases, the leakage pattern is in a direction which assists in producing the desired beam deflection.

The skewed angle between radial beam deflection and the beam deflection produced by the apparatuses of FIGS. 1 and 3 can be increased and/or selectively controlled by use of the apparatuses shown in FIG. 4. Additional rotation of the deflection vector is possible by further unbalancing the magnetic circuit. This can be achieved by increasing the core gap (or reluctance amplitude) by mechanical or electrical means.

In FIG. 4A, for example, the otherwise unused ferrite leg 34 has a small coil 80 connected in series opposition to a main coil 82, which otherwise corresponds to the coil 50 of FIGS. 1 and 3. The opposing series electrical connection between the coils 80 and 82 is illustrated in FIG. 4B. The resulting flux opposition produced by the

apparatus of FIG. 4 results in additional rotation of the flux field.

Other modifications to the embodiments disclosed herein which effect rotation of the flux between the internal pole pieces of a cathode ray tube by unbalancing the external magnetic circuit will be apparent to those skilled in the art. Such modifications are considered to be within the scope of the invention.

I claim:

1. A dynamic convergence assembly for deflecting an electron beam passing through a region bounded by two pole pieces having generally planar surfaces defining an axis equidistant therebetween, comprising:

core means having a first leg adjacent one of said pole pieces and a second leg adjacent the other of said pole pieces,

coil means wound about said core means for generating a magnetic flux field, and

unbalance means for producing a more concentrated magnetic flux field in one of said legs to cause an unsymmetrical distribution of magnetic flux between said pair of pole pieces, thereby deflecting said electron beam at a skew with respect to said equidistant axis.

2. The dynamic convergence assembly of claim 1 wherein said unbalance means comprises means mounting said coil means about only one of said core legs.

3. The dynamic convergence assembly of claim 2 wherein said unbalance means includes a pole shoe located between the core leg having the coil and the pole piece adjacent thereto, with the distance between the second leg and the pole piece adjacent thereto forming an air gap.

4. The dynamic convergence assembly of claim 2 wherein said core means comprises a generally U-shaped core with the first and second legs being generally L-shaped sections symmetrically disposed about said equidistant axis, the closest legs of the pair of L-shape sections being spaced apart to form an air gap therebetween, said single coil being wound about only one of said L-shaped sections.

5. The dynamic convergence assembly of claim 1 wherein said coil means comprises a first coil section wound about one of said core legs and a second coil section wound about the other of said core legs, and said unbalance means connects said first and second coil sections in series opposition to thereby unbalance the flux distribution in the pair of core legs and associated pole pieces.

6. The dynamic convergence assembly of claim 1 for a color television receiver having a cathode ray tube with a plurality of electron beams which individually pass through a plurality of pairs of symmetrical pole pieces, first and second core means for first and second of said electron beams and each having first and second legs adjacent the associated pairs of pole pieces associated with the electron beam controlled thereby, the first leg of the first core means and the second leg of the second core means being located in facing relationship, first and second coil means wound about said first and second core means, respectively, and first and second unbalance means for producing a more concentrated magnetic flux field in said facing legs.

7. The dynamic convergence assembly of claim 6 including third core means for a third of said electron beams, said third core means having first and second

legs adjacent the associated pairs of pole pieces associated with the third electron beam controlled thereby, third coil means wound about said third core means, and balance means for causing equal magnetic flux fields in said first and second legs of said third core means to thereby produce a symmetrical flux distribution.

8. In a color television receiver having a cathode ray tube with three electron beams respectively passing through regions bounded by three pairs of internal pole pieces, each pair comprising two pole pieces symmetrically disposed on opposite sides of an axis equidistant therebetween, a dynamic convergence system, comprising:

three convergence assemblies external to said cathode ray tube and each located adjacent different ones of said three pairs of internal pole pieces, each assembly generating a magnetic flux field for controlling the deflection of the electron beam passing between the associated pair of internal pole pieces, one of said convergence assemblies including balance means for generating a substantially balanced magnetic flux field between each of the two symmetrically disposed pole pieces associated therewith to deflect the associated electron beam along an axis parallel to said equidistant axis, and at least one other of said convergence assemblies including unbalance means for generating a substantially unbalanced magnetic flux field between each of the two symmetrically disposed pole pieces associated therewith to deflect the associated electron beam along an axis skewed to said equidistant axis.

9. The dynamic convergence system of claim 8 wherein each convergence assembly includes a generally U-shaped core means having a pair of extending legs each located adjacent a different one of the internal pole pieces associated therewith, and coil means wound on said core means for generating the magnetic flux field which passes through the legs and associated internal pole pieces to control the deflection of the associated electron beam.

10. The dynamic convergence system of claim 9 wherein said balance means comprises a pair of coil sections each wound on a different one of said legs to generate substantially equal concentrations of magnetic flux in said legs, said pair of coil sections corresponding to said coil means, and said unbalance means comprises means mounting said coil means on only one leg of the associated core means to produce a greater concentration of flux in the one leg.

11. The dynamic convergence system of claim 10 wherein the ends of the legs of said other convergence assembly are on approximately equal distance from the pole pieces, and said unbalance means further includes pole shoe means located in the space between one leg end and the associated internal pole piece.

12. The dynamic convergence system of claim 11 wherein said pole shoe means abuts the leg on which said coil means is mounted.

13. The dynamic convergence system of claim 10 wherein the remaining one of said three convergence assemblies includes unbalance means comprising means mounting said coil means on only one leg of the associated core means to produce a greater concentration of flux in the one leg.

14. The dynamic convergence system of claim 8 wherein the remaining one of said three convergence

assemblies includes unbalance means for generating a substantially unbalanced magnetic flux field between each of the two symmetrically disposed pole pieces associated therewith to deflect the associated electron beam along an axis skewed to an axis equidistant from the two symmetrically disposed pole pieces.

15. The dynamic convergence system of claim 14 wherein the unbalance means of said other convergence assembly and said remaining convergence assembly cause the pair of skewed axes to be substantially parallel.

16. The dynamic convergence system of claim 14 wherein said unbalance means of said other convergence assembly and said remaining convergence assembly are located to pass a stray magnetic flux field therebetween.

17. A dynamic convergence assembly for deflecting an electron beam passing between two pole pieces, comprising:

a horseshoe-type core means including a pair of side legs each adjacent a different one of said two pole pieces and an intermediate connecting leg extending between said pair of side legs at an end thereof opposite the two pole pieces, and a single convergence coil mounted around one of the 25 pair of side legs.

18. The dynamic convergence assembly of claim 17 wherein said intermediate connecting leg is interrupted by an air gap.

19. The dynamic convergence assembly of claim 17 including a second electron beam passing between a

second pair of pole pieces, a second horseshoe-type core means having a pair of side legs each adjacent a different one of said second pair of pole pieces and an intermediate connecting leg extending between said 5 pair of side legs at an end thereof opposite the second pair of pole pieces, and a single convergence coil mounted around one of the pair of side legs of said second horseshoe-type core means.

20. The dynamic convergence assembly of claim 19 10 wherein the single convergence coils are mounted on side legs which are located in facing relationship.

21. The dynamic convergence assembly of claim 17 including a sole shoe located between said one side leg which mounts the single convergence coil and the pole 15 piece adjacent thereto, an air gap between the opposite side leg and the pole piece adjacent thereto.

22. A convergence unit construction, comprising a horseshoe-type core having a single magnetic circuit including a pair of legs and an intermediate connecting portion extending between said legs at one end thereof, a single convergence coil mounted around said core.

23. A construction according to claim 22 in which said portion of said core extending between said legs is interrupted by a gap.

24. A construction according to claim 22 including three such cores spaced around a circle at substantially equal angular intervals, at least two of said cores having a single such convergence coil.
